United States Patent Office

Des. 192,828

Patented May 15, 1962

192,828

MOVIE FILM VIEWER

Charles C. Melton, Box 352, Ashfork, Ariz.

Filed July 10, 1961, Ser. No. 65,860

Term of patent 14 years

(Cl. D61—1)

Fig. 6

Fig. 1

Fig. 2

Fig. 3

Fig. 5

Fig. 4

FIG. 1 is a right side elevational view of a movie film viewer showing my new design;

FIG. 2 is a front elevational view thereof;

FIG. 3 is a left side elevational view thereof;

FIG. 4 is a bottom view thereof;

FIG. 5 is a rear elevational view thereof; and

FIG. 6 is a top plan view thereof.

The broken-line showing of film reels is for illustrative purposes only.

I claim:

The ornamental design for a movie film viewer, as shown.
